UNITED STATES PATENT OFFICE.

ISAAC Q. GURNEE, OF BUTLER, NEW JERSEY, ASSIGNOR TO THE BUTLER HARD RUBBER COMPANY, OF NEW YORK, N. Y.

DESIGN FOR AN EMBROIDERY-RING.

SPECIFICATION forming part of Design No. 28,301, dated February 15, 1898.

Application filed December 20, 1897. Serial No. 662,755. Term of patent 14 years.

To all whom it may concern:

Be it known that I, ISAAC Q. GURNEE, a citizen of the United States, residing at Butler, in the county of Morris and State of New Jersey, have invented and produced a new and original Design for an Embroidery-Ring, of which the following is a specification, reference being had to the accompanying drawing, forming a part thereof.

10 The drawing represents a perspective view of my embroidery-ring.

The leading feature of my design consists of an embroidery-ring having corrugations or serrations parallel with the side of the ring.

In the drawing, 1 represents the ring, having a series of parallel corrugations or serrations 2 formed thereon.

Having described my invention, what I claim as new, and desire to secure by Letters Patent, is—

20 The design for an embroidery-ring substantially as described.

In testimony whereof I affix my signature in the presence of two witnesses.

ISAAC Q. GURNEE.
